UNITED STATES PATENT OFFICE.

JOHN PATRICK FERRITER, OF JACKSONVILLE, FLORIDA, ASSIGNOR OF ONE-HALF TO
THOMAS J. PETERS, OF PETERS, FLORIDA.

ALTERNATING-CURRENT TELEGRAPH AND TELEPHONE DUPLEX.

1,251,208.

Specification of Letters Patent. Patented Dec. 25, 1917.

Application filed September 20, 1916. Serial No. 121,144.

To all whom it may concern:

Be it known that I, JOHN P. FERRITER, a citizen of the United States, and a resident of Jacksonville, in the county of Duval and State of Florida, have invented a new and Improved Alternating-Current Telegraph and Telephone Duplex, of which the following is a full, clear, and exact description.

This invention relates to telegraph and telephone systems, and has for its general object to provide a novel, reliable and efficient alternating current telegraph and telephone duplex which is adapted to operate on wires already in use, such as telephone circuits or direct current, single or multiplex telegraph circuits, or on a circuit used for no other service.

A more specific object is the provision of a junction coil of special construction, especially adapted for duplex work with a high frequency alternating current.

Still another object of the invention is to provide a novel combination of junction coil for an alternating current telegraph and telephone duplex system with a source of high frequency alternating current, a telephone transmitter and telephone receiver and appropriate circuit connections, whereby the junction coil can be connected with single or double wire circuits for telegraph or other service, or with single or double wire circuits limited to use with the duplex.

With such objects in view, and others which will appear as the description proceeds, the invention comprises various novel features of construction and arrangement of parts which will be set forth with particularity in the following description and claims appended hereto.

In the accompanying drawings, which illustrate certain embodiments of the invention and wherein similar characters of reference indicate corresponding parts in all the views,

Figure 1 is a diagrammatic view of the invention coupled to a direct current single or multiplex telegraph circuit;

Fig. 2 is a diagrammatic view showing the duplex coil connected with a metallic telephone circuit;

Fig. 3 is a diagrammatic view showing the duplex connected to a metallic two-wire circuit utilized for no other service;

Figs. 4, 5 and 6 are diagrammatic views showing different arrangements in which the

duplex is connected with the circuits through repeating coils;

Fig. 7 is a diagrammatic view showing the manner of modifying the instruments at an intermediate station when the duplex is used in a telegraph circuit; and

Fig. 8 is a fragmentary view showing diagrammatically the primary of the junction coil.

Referring to the drawings, A designates means for generating high frequency alternating current, B the junction coil and C the line wire. The source of high frequency alternating current may be an induction coil, Poulsen arc or the like, but in the present instance a buzzer transmitter, which constitutes the subject matter of my co-pending application, Serial Number 121,422, is shown. This buzzer transmitter consists of a long core 1 having wound thereon a low resistance winding 2, and both the winding and core are inclosed in a metal tube 3. At one end of the core is a make-and-break device in the form of a resilient contact 4 carrying an armature 5 and an adjustable contact 6, the contacts being connected in series with the winding 2, a key 7 and a battery 8, which latter is connected also with the winding 2. A telephone transmitter 9 is disposed at the end of the core 1 opposite from the interrupter, and includes an armature 10 which vibrates in harmony with the magnetic fluxes set up by the winding as the current is made and broken. The telephone transmitter 9 is connected in a primary circuit which includes a battery 11 and a winding 12 of an induction coil 13. The secondary 14 of the induction coil has one terminal connected to ground at 15 and the other terminal connected at 16 with the junction coil.

The buzzer transmitter constructed as described is preferably used in connection with the special form of junction coil herein set forth, as the buzzer transmitter is designed to eliminate brush currents which accompany the disruptive discharges of self-induced currents typical in buzzer transmitters. This absence of brush currents makes it possible to operate the herein-described duplex without materially interfering inductively with similar circuits or telephone circuits on adjacent wires, which has heretofore been impossible.

The junction coil B, which constitutes the

subject matter of my co-pending application, Serial Number 121,143, comprises an iron core 17 of suitable construction and indicated by the dotted lines, Fig. 1, and wound around this core are two primary windings 18 and 19 formed of twisted wires helically coiled, whereby current passing through the wires simultaneously will set up no magnetic action in the core, provided the 10 windings are balanced. The secondary 20 may be a single wire or a twisted pair of wires, and this secondary is inductively related to the primary windings by being coiled around the latter, although this relation is not shown in Fig. 1. The terminals of the secondary winding are connected with a telephone receiver *r*. One terminal of the winding 18 is connected by a wire 21 with the binding post 16, and the opposite terminal of the winding 19 is connected by a wire 22 with the same binding post 16. The other or free terminal of the primary 15 winding 18 is connected through a condenser 23 with a line wire *C*, while the free terminal of the winding 19 is connected to a condenser 24 with a variable resistance or rheostat *D*. The adjustable terminal 24' of this resistance *D* is connected to ground at 25. Intermediate points 26 and 27 of the resistance 20 are connected through condensers 28 and 29 with the ground at 30.

The use of a condenser between the junction coil and the line is for the purpose of avoiding interference of a direct current circuit on the same wire, and the condenser between the junction coil and the rheostat is to balance the capacity of the first-mentioned condenser.

By reason of the specially constructed 40 junction coil an outgoing current sets up no magnetic action in the core, and consequently sets up no current in the secondary winding which is connected with the receiver, assuming the duplex to be balanced. This type of junction coil is essential in alternating current duplex, as otherwise it takes very little unbalance in a coil to cause interference by the home signals.

To operate the device as a telephone duplex, no change in the layout is required, as the telephone transmitter adjacent to the buzzer transmitter and suitably connected with the transformer 13 is available for talking as well as for telegraphing. If desired, 45 however, a separate talking transmitter can be provided for telephoning by using a switching arrangement.

When operating on a wire already in use as a direct current single or multiplex telegraph circuit, a retardation coil 31 is placed in the line between the direct current instruments and the point where the alternating current set attaches to the line. The terminal of this retardation coil nearest the direct current set is connected to the earth at

32 through a condenser 33 of about one microfarad capacity. This arrangement flattens out the direct current impulses and prevents direct current interference in the alternating current receiver. The retardation coil also prevents any of the alternating current reaching the direct current instruments.

When the alternating current duplex is used on lines already carrying a direct current single circuit with various offices on the line, it is necessary, as shown in Fig. 7, to bridge the instruments at each intermediate office with a condenser 34, and a small resistance 35 is placed in series with the direct current instruments, such as the relay 36 and key 37. The condenser provides a path for the alternating current whether the key is open or closed. The resistance regulates the discharge of the condenser in such a manner as to materially assist the direct current relay's operation.

Fig. 2 illustrates a method of connecting the alternating current duplex to a metallic telephone circuit without interfering with said telephone circuit. 38 and 39 are each one microfarad condensers, one terminal of each being connected with a telephone wire. The other terminals of the two condensers are connected to the alternating current duplex or junction coil.

Fig. 3 illustrates a method of connecting the duplex to two wires 40 and 41 which are not in other service. This method can be used to advantage where a telegraph or telephone duplex is required on a long circuit and a pair of transposed wires are available, as, when transposed wires are used, no provision has to be made to overcome the effect of line noise.

Any desired number of alternating current duplex offices may be installed on a circuit, whether the line is in direct current use or not.

Figs. 4, 5 and 6 show a different arrangement of the alternating current instruments. There are no advantages in this system over the one previously described, but it is more convenient when telephone wires are used.

In these figures the terminal 42 of a junction coil primary 18 is connected to one winding 43 of a repeating coil *E*. The other terminal of this repeating coil winding is connected to one terminal of a winding 44 of a second repeating coil *F*. The other terminal of this second repeating coil winding 44 is connected with the terminal 45 of the junction coil primary 19. The terminals of the secondary winding 46 on the second repeating coil are connected with the terminals of a variable resistance 47, portions of which resistance have condensers 48 paralleling them. These are the balancing resistance and condensers. One terminal of the secondary winding 49 on the first re-

peating coil is connected to the line through a condenser 50, as in Fig. 4. The other terminal is connected to the earth at 51. One terminal of the talking coil secondary 5 14 is connected to the junction coil primaries. The other terminal is connected at 52 to the two windings 43 and 44 of the repeating coils E and F. In Fig. 5 the secondary winding of the repeating coil E has 10 its terminals connected to the two wires 40^a and 41^a of a circuit used for no other service; and in Fig. 6 the secondary winding has one terminal connected with the telephone line wires through condensers 38^a 15 and 39^a, and the other terminal connected to ground.

The advantage in a duplex arrangement for a telephone circuit is that, on account of the absence of interference from home signals in the receiver, a carbon transmitter repeater can be used effectively. Heretofore, such a repeater could not be used to advantage by reason of the howling the repeater transmitters set up after being in use 20 a few minutes. This trouble does not occur when a telephone duplex is used.

Having thus described my invention, I claim as new and desire to secure by Letters Patent:

- 30 1. In a system of the class described, the combination of a source of high frequency current, a junction coil having a primary formed of twisted wires helically wound, one end of one wire and the opposite end 35 of the other wire being connected together, an induction coil between the said source and the connected ends of the junction coil primary, a line wire circuit, condenser means between the line wire circuit and one 40 of the wires of the primary, a variable resistance having a grounded terminal, and a condenser between the other terminal of the variable resistance and the other wire of the primary.
- 45 2. In a system of the class described, the combination of a source of high frequency current, a junction coil having a primary formed of twisted wires helically wound, one end of one wire and the opposite end 50 of the other wire being connected together, an induction coil between the said source and the connected ends of the junction coil primary, a line wire circuit, condenser means between the line wire circuit and one of 55 the wires of the primary, a variable resistance having a grounded terminal, a condenser between the other terminal of the variable resistance and the other wire of the primary, and a receiver connected with the secondary side of the junction coil.
- 60 3. In a system of the class described, the combination of a source of high frequency current, a junction coil having a primary formed of twisted wires helically wound, one end of one wire and the opposite end

of the other wire being connected together, an induction coil between the said source and the connected ends of the junction coil primary, a line wire circuit, condenser means between the line wire circuit and one 70 of the wires of the primary, a variable resistance having a grounded terminal, a condenser between the other terminal of the variable resistance and the other wire of the primary, a receiver connected with the secondary side of the junction coil, and condensers connected with intermediate points of the variable resistance and connected with the grounded terminal of the variable resistance. 75

4. In a system of the class described, the combination of a source of high frequency alternating current, an induction coil having a winding connected with the said source, and another winding provided with 80 a grounded terminal, a junction coil including twisted wires helically wound, each connected with the ungrounded terminal of the second-mentioned winding forming a primary winding and a secondary winding 85 inductively related thereto, a receiver connected with the secondary winding, a line wire circuit connected with one of the said wires, a variable resistance connected with the other wire, a pair of condensers connected with different portions of the variable resistance, and a connection between the condensers and the other terminal of the variable resistance. 90

5. In a system of the class described, a 100 line wire including station instruments, a resistance in series with the instruments, a condenser bridging the instruments and resistance, a retarding coil in the line wire, a grounded condenser connected with the line 105 wire at the side thereof leading to the said station instruments, a junction coil connected with the line wire at the side of the retarding coil opposite from the grounded condenser, said junction coil having its primary formed of helically wound twisted wires, one end of one wire and the opposite end of the other wire being connected together, a condenser between one of the wires and the line wire, a condenser connected with the remaining end of the other wire, a secondary associated with the said primary winding, a receiver in circuit with the secondary, a variable resistance connected with the last-mentioned condenser 110 115 and having a grounded terminal, condensers connected with spaced portions of the variable resistance and also connected to ground, and a source of high frequency alternating current connected with the connected extremities of the two primary wires. 120

6. In a system of the class described, the combination of a junction coil having a secondary winding and a primary winding, said primary winding being formed of a 130

pair of twisted wires helically wound, a receiver connected with the secondary winding, one end of one wire and the opposite end of the other wire being connected together, a line circuit connected with the primary winding, means for generating high frequency current inductively connected with the connected ends of the wires of the primary winding of the junction coil and 10 including a transmitter.

7. In a system of the class described, the combination of a junction coil having a secondary winding and a primary winding, said primary winding being formed of a 15 pair of twisted wires helically wound, a receiver connected with the secondary winding, one end of one wire and the opposite end of the other wire being connected together, a line circuit connected with the primary winding, an induction coil having its secondary connected with the connected wires of the junction coil, a transmitter in the primary circuit of the induction coil, and means for producing high frequency

current in the primary circuit of the induct- 25
tion coil.

8. In a system of the class described, the combination of a junction coil having a secondary winding and a primary winding, said primary winding being formed of a 30 pair of twisted wires helically wound, a receiver connected with the secondary winding, one end of one wire and the opposite end of the other wire being connected together, a line circuit connected with the 35 primary winding, a buzzer transmitter, a controlling circuit therefor, means associated with the buzzer transmitter for eliminating brush currents, a telephone transmitter actuated by the buzzer transmitter, a source of continuous current connected with the telephone transmitter, and an induction coil having its primary in the telephone transmitter circuit and its secondary connected with the connected wires of the 40 junction coil.

JOHN PATRICK FERRITER.
